PASSIVE NONRECIPROCAL AMPLIFIER COUPLING NETWORK

Bernardus Dominicus Hubertus Tellegen and Willem Nijenhuis, Eindhoven, Netherlands, assignors to Hartford National Bank and Trust Company, Hartford, Conn., as trustee

Application February 26, 1952, Serial No. 273,514

Claims priority, application Netherlands March 1, 1951

5 Claims. (Cl. 179—171)

The invention relates to a circuit-arrangement including first and second amplifying tubes and a passive, electric quadripole connected between the output electrode of the first amplifying tube and the input electrode of the second amplifying tube. This quadripole has a transmission impedance Z_{21} having a predetermined dependence on frequency. It has for its object to provide the optimum transmission impedance Z_{21} obtainable with this prescribed frequency dependence at given values of the input capacity C_1 and the output capacity C_2 of the quadripole.

The invention is characterized by the use of a non-reciprocal electric quadripole, in which the quadripole impedances Z_{11} , Z_{12} , Z_{21} and Z_{22} fulfill the following conditions for all applied frequencies:

$$P = \sqrt{(R_{12} + R_{21})^2 + (X_{21} - X_{12})^2}$$

$$P = 2\sqrt{\frac{C_1}{C_2}R_{11}}$$

$$P = 2\sqrt{\frac{C_2}{C_1}R_{22}}$$

$$\frac{Z_{21} + Z'_{12}}{Z'_{21} + Z_{12}} = \frac{(b_1 - p)^2(b_2 - p)^2 \dots}{(b_1 + p)^2(b_2 + p)^2 \dots}$$

where R and X designate the real and the imaginary part of the associated impedance Z respectively; $p = j\omega$; ω = the angular frequency; P designates a never negative rational function in p^2 ; C_1 and C_2 are the input capacity and the output capacity respectively of the quadripole; $b_1, b_2 \dots$ are positive real constants or pairs of conjugate complex constants having a positive, real part; $Z'(p) = Z(-p)$.

The invention is based on the following considerations: The following relation prevails between the voltages V and the currents I at the input terminals 1 and the output terminals 2 respectively of a quadripole 3 (Fig. 1), having an input capacity C_1 and an output capacity C_2 :

$$(1) \quad \begin{aligned} V_1 &= Z_{11}I_1 + Z_{12}I_2 \\ V_2 &= Z_{21}I_1 + Z_{22}I_2 \end{aligned}$$

where Z_{11} and Z_{22} designate the input impedance and the output impedance respectively; Z_{21} is the transmission impedance and Z_{12} is the reaction impedance of the quadripole. The conventional, reciprocal quadripole fulfills the reciprocity relation: $Z_{12} = Z_{21}$.

A predetermined frequency variation of Z_{21} is, in general, prescribed for a quadripole connected between the output electrode of a first amplifying tube 5 and the input electrode of a second amplifying tube 6 (Fig. 2). It is desired that the optimum value for this transmission impedance Z_{21} be found using the given values of the capacities C_1 and C_2 which are produced by the wiring and the parasitic tube capacities. In other words, the transmission impedance Z_{21} is prescribed apart from a multiplicative constant. At the given input capacity C_1 and output capacity C_2 these constants are made as large as possible.

Bode solves this problem for a reciprocal quadripole (see Bode: Networks Analysis and Feedback Amplifier Design, chapter XVII) by assuming that the transmission impedance Z_{21} is completely given; he then determines the conditions in which the input capacity C_1 and the

2

output capacity C_2 become maximum in the given ratio C_1/C_2 . Subsequently the values of the impedances found can be multiplied by the same factor, so that the values of the input capacity and the output capacity become equal to the given values of C_1 and C_2 respectively. The transmission impedance Z_{21} is multiplied by the same factor, so that then the maximum value of this transmission impedance Z_{21} is found.

According to Bode the conditions for a realisable quadripole are:

$$\begin{aligned} R_{11}(\omega) &\gg 0; \\ R_{22}(\omega) &\gg 0; \text{ and} \\ R_{11}(\omega)R_{22}(\omega) &\gg R_{21}^2(\omega) \end{aligned} \quad (2)$$

where $R(\omega)$ indicates the real parts of the associated impedances $Z(j\omega)$ where ω designates the angular frequency and the conditions for maximum input capacity and output capacity are that with given C_1/C_2

$$\int_0^\infty R_{11}d\omega = \frac{\pi}{2C_1} \quad (3')$$

are minimum.

In order to fulfill these conditions, it is necessary, according to Bode, that

$$\sqrt{\frac{C_1}{C_2}}R_{11} = \sqrt{\frac{C_2}{C_1}}R_{22} = |R_{21}| \quad (4)$$

for each value of the frequency.

As is shown in Fig. 3, the real part R_{21} of the transmission impedance Z_{21} will, as a rule, not be invariably positive or negative, but it will have alternate polarities. However, since the virtual parts R_{11} and R_{22} of the input impedance and the output impedance respectively must be proportional to the absolute value of R_{21} , a kink, at the frequencies ω_1 , ω_2 and ω_3 , will occur in the frequency characteristic for these impedances. This proves that the associated network must, in theory, be of infinitely high order, even if Z_{21} is of finite order.

In the circuit-arrangement according to the invention, use is made of a non-reciprocal, electric quadripole. Such non-reciprocal, electric quadripoles are described, for example, in the U. S. patent applications Serial No. 13,506, now Patent No. 2,647,239, issued July 28, 1953, and Serial No. 241,835, filed August 14, 1951. They have the property that the impedances Z_{21} and Z_{12} are not equal. As a condition for a realisable quadripole is

$$\begin{aligned} R_{11} &\gg 0; \\ R_{22} &\gg 0; \text{ and} \\ R_{11}R_{22} &\gg \frac{1}{4}[(R_{12} + R_{21})^2 + (X_{21} - X_{12})^2] \end{aligned} \quad (2')$$

and the conditions for a maximum input capacity and output capacity are again that at given values of C_1/C_2 :

$$\int_0^\infty R_{11}d\omega = \frac{\pi}{2C_1} \quad (3')$$

are minimum.

The conditions (2') and (3') now lead to:

$$\sqrt{\frac{C_1}{C_2}}R_{11} = \sqrt{\frac{C_2}{C_1}}R_{22} = \frac{1}{2}\sqrt{(R_{12} + R_{21})^2 + (X_{21} - X_{12})^2} \quad (4')$$

where, in contradistinction to the corresponding condition (4) with reciprocal quadripoles the relation under the root now is formed by the sum of two squares, so that it becomes possible to form the complete square of a never negative, rational function P in ω^2 , where

$$P = \sqrt{(R_{12} + R_{21})^2 + (X_{21} - X_{12})^2} \quad (5)$$

so that:

$$P = 2\sqrt{\frac{C_1}{C_2}R_{11}} = 2\sqrt{\frac{C_2}{C_1}R_{22}} \quad (6)$$

in which case the network becomes of finite order, since

the impedances R_{11} and R_{22} must be describable, as required by quadripole theory, by a rational function, i. e. by the quotient of two polynomials.

Otherwise the maximum transmission impedance is found by determining in accordance with the conditions (3') and (4') at which values of R_{12} and X_{12} with given R_{21} and X_{21} the relation:

$$I = \int_0^\infty \sqrt{(R_{12} + R_{21})^2 + (X_{21} - X_{12})^2} d\omega \quad (7)$$

becomes minimum, i. e. the variation δI of the relation I at a variation δZ_{12} of the impedance Z_{12} must be equal to zero. By differentiation of the relation I for this variation is found:

$$\delta I = \int_0^\infty \operatorname{Re} \left(\frac{Z_{21} + Z'_{12}}{Z_{21} + Z_{12}} \delta Z_{12} \right) d\omega \quad (8)$$

where $Z'(p) = Z(-p)$ at $p = j\omega$, and Re designates the real part of the next following complex functions. The condition

$$\delta I \text{ is zero} \quad (9)$$

is fulfilled, according to one of the integral theses of Bode, if the integrant can represent the real part of a passive impedance function, of which the denominator exceeds the numerator by at least two degrees. This is the case, if

$$\frac{Z_{21} + Z'_{12}}{Z'_{21} + Z_{12}} = \frac{(b_1 - p)^2 (b_2 - p)^2 \dots}{(b_1 + p)^2 (b_2 + p)^2 \dots} \quad (10)$$

can be written, where $b_1, b_2 \dots$ designate positive real constants or pairs of conjugate complex constants having a positive real part.

It is found that a network in which the impedances Z_{21} and Z_{12} fulfill the condition (10) and which, consequently, has the optimum transmission impedance Z_{21} , fulfills at the same time the condition (5), so that it remains of finite order, it being assumed that Z_{21} remains of finite order.

The condition (4') is furthermore fulfilled, as can be proved, by each non-reciprocal quadripole, in which all losses are concentrated in only one resistor.

An example has been described of a non-reciprocal quadripole, connected between the anode circuit of a first amplifying tube and the grid circuit of a second amplifying tube, in which tuned oscillatory circuits are connected in parallel with the input terminals and the output terminals and in which furthermore a resistance coupling is provided between the primary terminals and the secondary terminals of the quadripole, so that a bandpass filter is obtained having an appreciably higher transmission impedance than is obtainable with a non-reciprocal quadripole. The invention has for its object to provide quadripoles which lead to another transmission function than is obtainable with the use of a bandpass filter comprising only two coupled circuits; it therefore explicitly excludes a claim for the aforesaid case.

A few examples of networks are described herein-after, which fulfill the conditions (5), (6) and (10) in accordance with the invention.

I. It is assumed that the desired transmission impedance is represented by

$$Z_{21} = \frac{1}{p^2 + ap + b^2} \quad (65)$$

The modulus of this transmission function is indicated in Fig. 4 for a high value of b/c . The impedance Z_{12} must then be represented by

$$Z_{12} = \frac{K}{p^2 + ap + b_2} \quad (70)$$

where, in accordance with the condition (10)

$$\frac{p^2 - ap + b^2 + Kp^2 + Kap + Kb^2}{p^2 + ap + b^2 + Kp^2 - Kap + Kb^2}$$

must be describable by

$$\frac{(b_1 - p)^2}{(b_1 + p)^2}$$

This is the case, if

$$K = \frac{a - 2b}{a + 2b}$$

For the quadripole impedances is thus found:

$$Z_{21} = \frac{1}{p^2 + ap + b^2}$$

$$Z_{12} = \frac{a - ab}{a + 2b} Z_{21}$$

$$Z_{11} = \frac{a + 2p}{a + 2b} \sqrt{\frac{C_2}{C_1}} Z_{21}$$

$$Z_{22} = \frac{a + 2p}{a + 2b} \sqrt{\frac{C_1}{C_2}} Z_{21}$$

This network may be obtained, as is shown in Fig. 5, by assuming that the capacities C_1 and C_2 are identical. The values in this case are:

$$\begin{aligned} \text{Capacities } C &= b + \frac{1}{2}a \\ \text{gyration conductance } s &= b(b + \frac{1}{2}a) \\ \text{resistor } R &= \frac{1}{2}a(b + \frac{1}{2}a) \end{aligned}$$

Compared with a reciprocal network, in which

$$R_{11} = \frac{b^2 + p^2}{(b^2 + p^2)^2 - a^2 p^2}$$

now a network of finite order is found, of which the transmission impedance is a few times higher.

II. It is assumed that the desired transmission impedance is represented by:

$$Z_{21} = \frac{Y + b}{p^2 + 2pY + b^2}$$

where b is a real positive constant and Y is an admittance, equal to the quotient f/g of two polynomials, of which the numerator is of the same degree as the denominator or is one degree lower than the denominator. The corresponding network is shown in Fig. 6 and Fig. 7 respectively. Referring to Fig. 6, a gyration coupling is connected in parallel with the input terminals and the output terminals, having input capacity C_1 and output capacity C_2 , which are again assumed to be identical and the admittance Y between one of the primary terminals and one of the secondary terminals is connected. In order to fulfill the condition (10) the impedance Z_{12} is found to be necessarily equal to

$$\frac{Y - b}{p^2 + 2pY + b^2}$$

since, according to this condition

$$\frac{(Y + b)(p^2 - 2pY + b^2) + (Y' - b)(p^2 + 2pY + b^2)}{(Y' + b)(p^2 + 2pY + b^2) + (Y' - b)(p^2 - 2pY' + b^2)}$$

must be describable by

$$\frac{(b - p)^2}{(b + p)^2}$$

which is the case, if the factor $Y + Y'$ is distributed. In the diagrams shown in Figs. 6 and 7 the capacities C are 1, the gyration conductivity $s = b$ and according to Fig. 7, the impedance Z is

$$\frac{Y}{b^2}$$

III. It is assumed that the desired transmission impedance can be represented by:

$$Z_{21} = \frac{(f + g)H}{fU + gE}$$

where f and g are arbitrary polynomials, H a polynomial, or the quotient of two polynomials having only even-numbered potency terms of p (consequently $H' = H$) and E and U are the even-numbered and the odd-numbered potency terms respectively of p of the polynomial, which is obtained after working out the relation $(b_1 + p)^2 (b_2 + p)^2 \dots$, where b_1 and b_2 are positive, real constants or pairs of conjugate complex constants having a positive real part. If in this case Z_{12} is chosen to be

$$Z_{12} = \frac{(f - g)H}{fU + gE}$$

the condition (10) is found to be fulfilled, since after

division of the factor (fg' and gf') the relation changes, in accordance with this condition, into:

$$\frac{E-U}{E+U} = \frac{(b_1-p)^2(b_2-p)^2 \dots}{(b_1+p)^2(b_2+p)^2 \dots}$$

The above relation for Z_{21} may, if desired, be changed into:

$$Z_{21} = \frac{fE+gU/p}{fg+g} \cdot H$$

In the corresponding diagram of Fig. 8, for example, the transmission impedance may be described in the relation given, if the impedances X are equal reactances, which are substantially free from losses and if Y is an arbitrary admittance in which substantially all damping of the quadripole is concentrated.

What we claim is:

1. A circuit arrangement comprising first and second amplifier stages, each stage including an electron discharge tube having a control electrode and an output electrode, and a passive non-reciprocal quadripole coupled between the output electrode of the first stage and the input electrode of the second stage, said quadripole possessing electrical characteristics in which the following quadripole relations subsist for all applied frequencies:

$$P = \sqrt{(R_{12} + R_{21})^2 + (X_{21} - X_{12})^2} = 2\sqrt{\frac{C_1}{C_2} R_{11}} = 2\sqrt{\frac{C_2}{C_1} R_{22}}$$

$$\frac{Z_{21} + Z'_{12}}{Z_{21} + Z_{12}} = \frac{(b_1 + p)^2(b_2 - p)^2 \dots}{(b_1 + p)^2(b_2 + p)^2 \dots}$$

where

ω =the angular frequency

$p=j\omega$

P =a never negative rational function in p^2

$Z'(p) = Z(-p)$

Z_{11} =the quadripole input impedance

Z_{12} =the quadripole output impedance

Z_{21} =the quadripole transmission impedance

Z_{22} =the quadripole reaction impedance

C_1 =the input capacitance of the quadripole

C_2 =the output capacitance of the quadripole

$R_{11}, R_{12}, R_{21}, R_{22}$ =the real part of impedances $Z_{11}, Z_{12}, Z_{21}, Z_{22}$, respectively

$X_{11}, X_{12}, X_{21}, X_{22}$ =the imaginary part of impedances

$Z_{11}, Z_{12}, Z_{21}, Z_{22}$, respectively

b_1, b_2 =constants.

2. A circuit arrangement as set forth in claim 1 wherein b_1 and b_2 are positive real constants.

3. A circuit arrangement as set forth in claim 1 wherein b_1 and b_2 are pairs of conjugate complex constants having a positive real part.

4. A circuit arrangement as set forth in claim 1 wherein said quadripole includes at least one gyrator coupled between said input and output electrodes and only one damping resistor connected between said input and output electrodes, wherein the damping of said quadripole is substantially concentrated in said one damping resistor.

5. A circuit arrangement as set forth in claim 1 wherein

$$Z_{21} = \frac{(f+g)H}{fU+g}$$

where

20 f and g =arbitrary polynomials

H =a polynomial having only even powers of p

E and U =the polynomials formed by the even and odd powered terms respectively of $(b_1+p)^2(b_2+p)^2 \dots$

25 and wherein said quadripole includes a symmetrical connection having reactances in parallel with the input and output terminals of the quadripole, said connection including a gyrator and only one damping impedance in which the damping of said quadripole is substantially concentrated.
